CHANNEL

Application filed September 5, 1930. Serial No. 479,866.

The invention disclosed in this application relates to flexible channel provided with a soft covering or coating for receiving and guiding window panes generally, and particularly those of motor vehicles.

The object of the present invention is to improve the core of flexible window channel so that it may be twisted or flexed in its application to the window groove and may be permanently set in bent form in this groove so as to follow nicely the configuration of the door or window no matter what that configuration may be. It is especially useful in cases where the window frame has a shape other than the normal rectangular configuration.

Specifically the invention contemplates a molding comprising a core consisting of continuous edge portions for engagement with the window pane and transverse connecting webs or bars formed to provide elongated triangular openings between them which permit of the desired bending and flexing. This core in the flat is covered with rubber and upon this is secured an outer casing of felt. The flat stock thus formed is then formed up in channel shape ready for use.

The invention is particularly well disclosed in the following description, drawing and claims.

Referring to the drawing, Fig. 1 is a perspective view of a piece of channel; Fig. 2 is a perspective view of a piece of core; and Fig. 3 is a view in reduced scale of the metallic strip core before it is formed into substantially U-shape, as shown in Fig. 2.

In the drawing the channel comprises a core preferably made of a strip of spring metal stamped out to form continuous edge portions 1, connected by transverse narrow webs 2 arranged at angles to each other to provide angular openings between them as indicated at 3. This core is covered with a coating of rubber, indicated at 4, and thereafter this composite structure is covered with an outer covering of felt, indicated at 5, which envelopes the entire channel and is held in place by the rubber until the same is vulcanized. This produces channel stock which is afterwards formed into U-shape comprising

the base, generally indicated at A, and the side portions, generally indicated at B, which are bent to provide lips C.

In being applied, the channel may be twisted or bent to bring it in place and such twisting or bending may occur not only sideways, but may be in a back and forth direction in a plane corresponding to that to be occupied by the window pane. When bent properly it will conform nicely to various shapes and will retain such configuration.

Having described my invention, I claim:

1. A core for a window channel made up of a strip of thin flexible metal and stamped out to provide continuous edge portions and transverse straps extending at an angle to each other to provide openings therebetween, whereby the channel may be flexed back and forth in the plane to be occupied by the window pane.

2. A metal core for a window channel, comprising a generally channel shaped thin flexible metal strip having continuous longitudinal edge portions, which portions constitute the free or upper edge portions of the side walls of said channel member, said edge portions being connected by transverse, angularly extending straps longitudinally spaced to provide transverse openings therebetween, each of said openings extending transversely from a point within one side wall of said channel member through the bottom thereof to a point within the other side wall of said channel member, whereby said channel member may be flexed back and forth in the plane to be occupied by the window pane which said channel member is adapted to receive.

3. A metal core for a window channel, comprising a generally channel shaped thin flexible metal strip having continuous longitudinal edge portions, which portions constitute the free or upper edge portions of the side walls of said channel member, said edge portions being connected by transverse, angularly extending straps longitudinally spaced to provide transverse openings therebetween, each of said openings extending transversely from a point within one side wall of said channel member through the bottom thereof to a point within the other side wall of said channel member.

channel member, whereby said channel member may be flexed back and forth in the plane to be occupied by the window pane which said channel member is adapted to receive, alternate straps being arranged in parallel relation.

4. A metal core for a window channel, comprising a generally channel shaped thin flexible metal strip having continuous longitudinal edge portions, which portions constitute the free or upper edge portions of the side walls of said channel member, said edge portions being connected by transverse straps angularly extending and longitudinally spaced to provide generally triangular shaped openings therebetween, each of said openings extending transversely from a point within one side wall of said channel member through the bottom thereof to a point within the other side wall of said channel member, whereby said channel member may be flexed back and forth in the plane to be occupied by the window pane which said channel member is adapted to receive.

25 5. A metal core for a window channel, comprising a generally channel shaped thin flexible metal strip having continuous longitudinal edge portions, which portions constitute the free or upper edge portions of the side walls of said channel member, said edge portions being connected by transverse straps angularly extending and longitudinally spaced to provide generally triangular shaped openings therebetween, each of said openings extending transversely from a point within one side wall of said channel member through the bottom thereof to a point within the other side wall of said channel member, whereby said channel member may be flexed back and forth in the plane to be occupied by the window pane which said channel member is adapted to receive, the wider end of each of said openings lying between the narrower ends of adjacent openings.

40 45 In testimony whereof I hereby affix my signature.

WALTER S. GAINES, JR.
